MACHINE FOR AND METHOD OF MAKING
RAISED BOTTOM BASKETSSylvester H. Hunt, Norfolk, Va., assignor to
Farmers Incorporated, Norfolk, Va., a corpora-
tion of Virginia

Application August 2, 1940, Serial No. 349,879

12 Claims. (Cl. 1—13.6)

The invention relates to improvements in machines for the methods of making baskets, such as a raised bottom basket including side staves, an inside bottom hoop, an outside bottom hoop, middle and top hoops, and a bottom disposed adjacent the inside bottom hoop.

The primary object of the invention is to provide an improved machine for and method of stapling the bottom in the basket at the time the staves and hoops are stitched together. This object is accomplished by combining a pair of staplers into a double stapler head working in unison with the other staplers that stitch the middle and top hoops of the basket, and so arranged that a given one of the pair drives a staple into the bottom hoop at the usual angle, so that the head of the head of the staple is diagonally crosswise the hoop, and the other one of the pair drives a staple straight into the bottom, so that the head of the staple is parallel to the plane of the basket bottom, simultaneously with alternate operations of the given stapler and in staggered relation with pairs of staples driven thereby. The basket formed by the improved machine and method affords a neat and uniform structure at a considerable saving in labor.

Another object of the invention is to provide a machine of the character described having a double stapler head including a long stapler and a short stapler, the difference in length of the staplers corresponding to the thickness of the outside bottom hoop so that the long and short staplers may drive staples flush with the staves and outside bottom hoop respectively.

The invention is particularly useful in the economical manufacture of sturdy baskets having good appearance and devoid of the so-called "shiners" (legs of staples initially driven radially into the basket bottom, but which have burst out at the upper or lower surfaces of the basket bottom and likely to injure or snag fruit or other produce shipped in the basket, or injure persons handling the basket). The invention makes possible the use of thin, narrow outside bottom hoops of comparatively inexpensive material such as gum, without likelihood of the hoop material splitting, in contradistinction to the heavier and wider hoops used in the barrel industry, frequently made of elm. The invention contemplates driving, by use of the long stapler, a line of spaced staples fastening the staves only to the basket bottom, without the legs of the staples passing thru the outside bottom hoop.

Other objects and advantages of the invention

will be apparent during the course of the following detailed description, taken in connection with the accompanying drawings, forming a part of this specification, and in which drawings,

5 Figure 1 is a fragmentary view partly in side elevation and partly in vertical section of a basket stapling machine provided with the double stapler head.

10 Figure 2 is a diagrammatic view showing the relation of the stapler heads to lines of staples driven thereby.

Figure 2A is a fragmentary sectional detail view of a basket and showing a staple driven obliquely into the outside bottom hoop, stave and inside bottom hoop and a staple driven straight into the basket bottom transversely of the stave.

15 Figure 3 is a fragmentary bottom plan view showing the staplers and wire feed means therefor.

20 Figure 4 is a fragmentary view in elevation showing in an advanced position ratchet means intermittently actuating the wire feed means.

Figure 5 is a fragmentary view partly in elevation and partly in vertical section and showing 25 the ratchet means in a retracted position.

Figure 6 is a top plan view of the double stapler head.

Figure 7 is a view in front elevation of the double stapler head.

30 Figure 8 is a vertical sectional view of the double stapler head, taken substantially on the angular line 8—8 of Figure 6.

Figures 9 and 10 are end elevation and side perspective views respectively of the stapler assembly for the double stapler head.

35 Figure 11 is a view partly in elevation and partly in vertical section of the double stapler head, with one of the side plates removed to disclose details, the parts being shown in the up-stroke position.

40 Figure 12 is a similar view in elevation but showing the parts in the down-stroke position.

Figure 13 is a bottom plan view of the assembly shown in Figure 11.

45 In the drawings, which for the purpose of illustration show only a preferred embodiment of the invention, and wherein similar reference characters denote corresponding parts throughout the several views, the letter A generally designates the improved machine and B the raised bottom basket.

50 The basket B includes a plurality of staves 15, inside and outside bottom hoops 16, 17 secured to the staves by staples 18, a middle hoop 19 secured to the staves by staples 20, inside and out-

55

side top hoops 21, 22 secured to the staves by staples 23, and a bottom 24 secured to the staves by staples 25.

My improved machine A is of the general character shown and described in U. S. Patent 1,643,287 and 1,682,769, except that instead of employing three single staplers, I utilize two single staplers 30 of conventional construction which stitch or staple the middle and top hoops in the usual way and a special double stapler 31 so constructed and arranged as to stitch or staple the bottom hoops to the staves and also to staple the basket bottom to the staves only, adjacent the bottom hoops.

The machine A includes the usual pedestal 35 carrying a crank shaft 36 to which is pivoted a pitman 37 connected to a vertically reciprocable shaft 38 carrying a horizontal beam 43, to which the upper ends of the staplers 30, 31 are attached. Fixedly carried beneath the beam 43 is a stationary bar 44 supporting the staplers 30, 31 in the usual manner. Rotatably mounted on the pedestal is a rotary basket form 45 of any suitable type, such as shown and described in my U. S. patent application, Serial Number 314,702, or in U. S. Patent 2,098,049. In the example shown, the form 45 includes rings 46-48 and is provided with intermittent drive mechanism 49 of the usual pawl and ratchet type actuated thru a link 50 connected to the beam 43. Removably disposed adjacent the form 45 is a flanged rotary disc 51 adapted to rotatably support the basket bottom and the inside bottom hoop in position for stapling. The staves and outer hoops of the basket may be fed into stapling position on the form 45 by the mechanism shown and described in my U. S. patent application, Serial Number 314,702.

Referring to the special double stapler 31, the same comprises a frame or casing 55 including a rear section 56 for attachment to the stationary bar 44 and a pair of angularly disposed sections 57, 58 removably secured, as by cap screws 59, to the rear section 56. Reciprocably slideable interiorly of the frame or casing 55 are staple former and driver assemblies 60, 60a, co-operable with the usual loop bars 61 to form and drive staples upon descent of the assemblies 60, 60a relative to the frame or casing 55. From an inspection of Figure 8 of the drawings it will be seen that the loop bars 61 are pivoted on pins 62 carried by the casing sections 57, 58 for swinging into and out of their loop forming relation to the former blades 63 of the assemblies 60, 60a. The driver members 64 of these assemblies are pivotally supported at their upper ends by pins 65 to which are fixed depending rods 66 having their lower ends disposed in sockets 67 in the former blades 63. Encircling the rods 66 are expansion coil springs 68 urging the former blades 63 downwardly into engagement with abutment portions 69 of the driver members 64. Pivoted as at 104, to each driver member 64 is the usual latch 70, urged into latching engagement with the upper end of its associated former blade 63 by the usual leaf spring shown at 71 in Figures 10, 11 and 12 and cammed out of latching engagement during descent of the former and driver assemblies by the usual cam 72 fixed to the stationary casing or frame, as shown in Figures 6, 7, 11 and 12.

At their upper ends, the former and driver assemblies 60, 60a are connected by the pins 65 to spaced angularly disposed depending legs 73 of a yoke 74 having upwardly projecting lugs 75

for pivotal connection, as by a pin 76, to a link 77 attached, as shown in Figure 1, to the upper beam 43, as by a suitable bracket 78.

Attention is invited to Figures 2 and 3, where-
5 in it will be noted that the staple former and driver assembly 60 for stapling the bottom hoops of the basket is obliquely arranged so that the heads of the staples 18 when driven will be diagonally crosswise the hoop 16 and is centered
10 on a line 80 intersecting the single staplers 30 that staple the middle and top hoops of the basket. The auxiliary staple former and driver assembly 60a of the double stapler 31 for stapling the basket bottom is not only disposed inwardly
15 of the assembly 60 but also forwardly of the stapling line 80 so as to drive staples 25 in staggered relation to the staples 18, and with the legs of the staples 25 extending thru the staves only, and not thru the bottom hoop 16. In pro-
20 ducing the basket B shown in Figure 1, the basket form is of course advanced one step for each stapling operation and the former and driver assembly 60a is disposed a half step in advance of the stapling line 80. The single and
25 double staplers 30, 31 of course operate simulta-
30 neously but the former and driver assembly 60a receives staple wire only on alternate opera-
35 tions so as to skip every other staple. It will therefore be understood that in one stapling operation one each of the staples 18, 20 and 23
35 will be simultaneously inserted along the line 80 adjacent the forward side margin of a stave, and in a succeeding operation, one each of the staples 18, 20 and 23 will be inserted adjacent the trail-
40 ing side margin of the stave, and in addition a
45 staple 25 will be simultaneously driven into the basket bottom intermediate the side margins of the stave.

From an inspection of Figures 10 and 12, it
40 will be seen that the former and driver assembly
45 60a extends below the assembly 60, the difference
50 in length of the assemblies 60, 60a being sub-
55 stantially equal to the thickness of the outside
60 bottom hoop so that the staples 18 and 25 will
65 be driven flush with the outside bottom hoop
70 indicated by the line A-A and with the stave,
75 as indicated by the line B-B in Figure 12.

Any type of mechanism may be employed for
50 feeding the stapling wire successively to the
55 single staplers and to the assembly 60 of the
60 double stapler while supplying the stapling wire
65 to the assembly 60a for alternate stapling opera-
70 tions. In the example shown in Figures 1, 3,
75 4 and 5, the wire feed means 85 is actuated by
80 the usual ratchet operating rod 86 and eccentric
85 cam 87 on the shaft 36. Rotatably mounted as
90 by bearing brackets 88 on the beam 44 is a sleeve
95 encircling a shaft 90 rotatable therewithin,
95 and of a length to project from the ends of the
100 sleeve. Fixed on the sleeve 89 are feed rollers
105 91 adapted to advance the wires 92 thru guides
110 93 to the single staplers 30 and to the stapling
115 assembly 60 of the double stapler. Fastened on
120 the shaft 90 is a feed roller 94 adapted to advance
125 a wire 95 thru a guide 96 to the stapling assem-
130 bly 60a. Fastened on the sleeve 89 and shaft
135 90 are ratchets 97 and 98, respectively, cooper-
140 able with a pawl 99 bridging both ratchets and
145 actuated by the rod 86 thru a lever 100 pivoted
150 intermediate its ends on the sleeve 89. All the
155 teeth 101 of the ratchet 98 lie along a circle
160 concentric with the shaft 90, whereas alternate
165 teeth 102 of the ratchet 97 lie outwardly of said
170 circle with the intermediate teeth 103 alignable
175 with the teeth 101. Thus it will be understood

that the ratchet 97 will be advanced one tooth for each stroke of the ratchet operating rod 86 whereby to impart motion to each of the feed rollers 91, whereas the ratchet 98 will be advanced one tooth for each two strokes of rod 86, due to elevation of the pawl 99 out of engagement with the ratchet 98 upon engagement of the pawl with the alternate teeth 102 of the ratchet 97, whereby to operate the feed roller 94 simultaneously with alternate operations of the feed rollers 91. It will therefore be noted that I have provided an improved double stapler wherein one staple former and driver 60 operates successively to insert oblique staples thru the bottom hoops of a raised bottom basket and wherein another staple former and driver 60a operates alternately to insert horizontal staples into the staves and basket bottom, with the horizontal staples disposed half way between pairs of oblique staples.

Various changes may be made in the form of invention herein shown and described without departing from the spirit of the invention or the scope of the following claims.

I claim:

1. In a machine for making a raised bottom basket of the type including side staves, an inside bottom hoop, an outside bottom hoop and a bottom disposed inwardly adjacent the inside bottom hoop, mechanism for supporting the basket materials in position for stapling, a main stapler successively operable to drive a line of spaced staples fastening the hoops and staves, and an auxiliary stapler, operable simultaneously with alternate operations of the main stapler, to drive an adjacent line of spaced staples fastening the staves only, to the bottom.

2. A structure as specified in claim 1, said auxiliary stapler being longer than the main stapler, the difference in length being substantially equal to the thickness of the outside bottom hoop.

3. In a machine for making a raised bottom basket of the type including side staves, an inside bottom hoop, an outside bottom hoop and a bottom disposed inwardly adjacent the inside bottom hoop, mechanism for supporting the basket materials in position for stapling, a main stapler for driving a line of spaced staples fastening the hoops and staves, an auxiliary stapler for driving a line of spaced staples fastening the staves only, to the bottom, means simultaneously actuating the main and auxiliary staplers, feed means successively supplying staple wire to said main stapler for successive operations thereof and feed means alternately supplying staple wire to said auxiliary stapler for alternate operations thereof.

4. A structure as specified in claim 3, said auxiliary stapler being longer than the main stapler, the difference in length being substantially equal to the thickness of the outside bottom hoop.

5. In a machine for making a raised bottom basket of the type including side staves, and inside bottom hoop, and outside bottom hoop and a bottom disposed inwardly adjacent the inside bottom hoop, mechanism for supporting the basket material in position for stapling, a main stapler, including a staple former and driver disposed to drive staples obliquely of the hoops, successively operable to drive a line of spaced staples passing said hoops and staves, and an auxiliary stapler, including a staple former and driver disposed to drive staples parallel to the

plane of said bottom, operable simultaneously with alternate operations of said main stapler, to drive an adjacent line of spaced staples fastening the staves only, to the bottom.

6. In a machine for making a raised bottom basket of the type including side staves, and inside bottom hoop, an outside bottom hoop and a bottom disposed inwardly adjacent the inside bottom hoop, mechanism for supporting the basket materials in position for stapling, a main stapler successively operable to drive a line of spaced staples fastening the hoops and staves, and an auxiliary stapler offset diagonally with respect to said main stapler and laterally with respect to the zone of operation of said main stapler, said auxiliary stapler operable simultaneously with alternate operations of said main stapler to drive a line of spaced staples in staggered relation to the staples of said first mentioned line of staples, for fastening the staves only, to the bottom.

7. In a machine for making a raised bottom basket of the type including side staves, an inside bottom hoop, an outside bottom hoop and a bottom disposed inwardly adjacent the inside bottom hoop, mechanism for supporting the basket materials in position for stapling, a main stapler including a staple former and driver disposed to drive staples obliquely of the hoops, successively operable to drive a line of spaced staples fastening said hoops and staves, an auxiliary stapler including a staple former and driver disposed to drive staples parallel to the plane of said bottom, to drive an adjacent line of spaced staples fastening the staves only, to the bottom, means simultaneously actuating the main and auxiliary staplers, feed means successively supplying staple wire to said main stapler for successive operations thereof, and feed means alternately supplying staple wire to said auxiliary stapler for alternate operations thereof.

8. In a machine for making a raised bottom basket of the type including side staves, an inside bottom hoop, an outside bottom hoop, and a bottom disposed inwardly adjacent the inside bottom hoop, mechanism for supporting the basket materials in position for stapling, a main stapler for driving a line of spaced staples fastening the hoops and staves, an auxiliary stapler offset diagonally with respect to said main stapler and laterally with respect to the zone of operation of said main stapler, for driving a line of spaced staples in staggered relation to staples of said first mentioned line of staples, for fastening the staves only, to the bottom, means simultaneously actuating the main and auxiliary staplers, feed means successively supplying staple wire to said main stapler for successive operations thereof, and feed means alternately supplying staple wire to said auxiliary stapler for alternate operations thereof.

9. In a machine for making a raised bottom basket of the type including side staves, an inside bottom hoop, an outside bottom hoop, a plurality of additional hoops spaced above said outside bottom hoop, and a bottom disposed adjacent the inner bottom hoop, mechanism for supporting the basket material in position for stapling, a main stapler, including a staple former and driver disposed to drive staples obliquely of the hoops, successively operable to drive a line of spaced staples adjacent the longitudinal margins of the staves for fastening

the bottom hoops and staves, additional staplers operable simultaneously with the main stapler to drive lines of spaced staples adjacent the longitudinal margins of the staves for fastening the additional hoops to the staves, and an auxiliary stapler, including a staple former and driver disposed to drive staples parallel to the plane of said bottom, operable simultaneously with alternate operations of the main stapler, to drive a line of spaced staples at points substantially midway between the longitudinal margins of the staves for fastening the staves only, to the bottom.

10. The method of making a raised bottom basket of the type including staves, an inside bottom hoop contacting the inner faces of the staves adjacent their ends, an outside bottom hoop contacting the outer faces of said staves adjacent their ends and lying in substantially the same plane as the inside bottom hoop, and a basket bottom contacting the inner hoop, which includes supporting the basket materials in position for stapling, successively driving a line of staples with the legs thereof extending thru the outside hoop, the staves adjacent the longitudinal margins thereof and at least into the inner hoop, and with the same driving force used in driving alternate staples of said line of staples, driving a line of staples with their legs extending thru the staves at points intermediate the longitudinal margins of the staves and offset from said outside hoop, and into the basket bottom.

11. The method of making a raised bottom basket of the type including staves, an inside

bottom hoop contacting the inner faces of the staves adjacent their ends, an outside bottom hoop contacting the outer faces of said staves adjacent their ends and lying in substantially the same plane as the inside bottom hoop, and a basket bottom contacting the inner hoop, which includes supporting the basket materials in position for stapling, successively driving a line of staples with the legs thereof extending thru the outside hoops, the staves, and at least into the inner hoop, and with the same driving force used in driving alternate staples of said line of staples, driving a line of staples with their legs extending thru the staves at points offset from said outside hoop, and into the basket bottom.

12. The method of making a raised bottom basket of the type including staves, an inside bottom hoop contacting the inner faces of the staves adjacent their ends, an outside bottom hoop contacting the outer faces of said staves adjacent their ends and lying in substantially the same plane as the inside bottom hoop, and a basket bottom contacting the inner hoop, which includes supporting the basket materials in position for stapling, successively driving a line of staples with the legs thereof extending thru the outside hoop, the staves, and at least into the inner hoop, and with the same driving force used in driving said line of staples, driving a line of staples with their legs extending thru the staves at points offset from said outside hoop and into the basket bottom.

SYLVESTER H. HUNT.
